CLAIM

We claim the ornamental design for a blender jar, as shown and described.

DESCRIPTION

FIG. 1 is a first side perspective view of a blender jar of the present disclosure;

FIG. 2 is a second side perspective view of the blender jar of FIG. 1;

FIG. 3 is a front perspective view of the blender jar of FIG. 1;

FIG. 4 is a rear perspective view of the blender jar of FIG. 1;

FIG. 5 is a first side elevational view of the blender jar of FIG. 1;

FIG. 6 is a second side elevational view of the blender jar of FIG. 1;

FIG. 7 is a third side elevational view of the blender jar of FIG. 1;

FIG. 8 is a fourth side elevational view of the blender jar of FIG. 1;

FIG. 9 is a top plan view of the blender jar of FIG. 1; and, FIG. 10 is a bottom plan view of the blender jar of FIG. 1. The broken lines depict portions of the article that form no part of the claimed design.
